Attorney

UNITED STATES PATENT OFFICE.

CARL WHITE, JR., OF CHATTANOOGA, TENNESSEE, ASSIGNEE TO LUCEY MANUFACTURING CORPORATION, OF CHATTANOOGA, TENNESSEE, A CORPORATION OF TENNESSEE.

AUTOMATIC FINGER-LATCH ELEVATOR.

1,278,287.

Specification of Letters Patent. Patented Aug. 20, 1918.

Application filed May 6, 1918. Serial No. 222,766.

To all whom it may concern:

Be it known that I, CARL WHITE, Jr., a citizen of the United States, residing at Chattanooga, in the county of Hamilton and State of Tennessee, have invented certain new and useful Improvements in Automatic Finger-Latch Elevators, of which the following is a specification.

This invention relates to improvements in elevator clamps used in well drilling, for raising and lowering the tubing or casing, said clamps being supported by means of bail-links connected to the hoisting mechanism and the body of the clamps being detachably secured to the casing. These devices are commonly termed "casing elevators."

The primary object of the invention is to provide an elevator with pivoted clamp sections and with novel locking means which will automatically lock the sections together when swung to a closed position and will positively remain locked until released by the attendant.

Another object of the invention is to provide locking means which are so designed that the elevator cannot be opened while the same is in operation, owing to the fact that the coupling or joint of the casing rests on the upper face of the elevator, holding the jaws in positive locked position.

Still another object of the invention resides in the simplicity and construction of the locking mechanism which greatly facilitates the unlocking and opening of the elevator.

With the foregoing and other objects in view, which will appear as the description proceeds, the invention resides in the combination and arrangement of parts and in the details of construction hereinafter described and, claimed, it being understood that changes in the precise embodiment of the invention herein described can be made within the scope of what is claimed, without departing from the spirit of the invention.

The invention is illustrated in the accompanying drawings.

Figure 1 is a perspective view of the elevator in closed position.

Fig. 2 is a sectional elevation looking at the inside of the right hand jaw with the elevator in an open position.

Fig. 3 is an elevation looking at the in-

side of the left hand jaw with the elevator in an open position.

In the drawings A represents a section of a well tubing or casing, to the upper end of which is connected a coupling or joint B, connecting the said casing A to the adjacent upper section of same.

1 designates the elevator proper which is composed of the jaws 2 and 3 of semi-circular shape and which when brought together in a closed position, form a cylindrical opening to coincide with the outside diameter of the casing to be clamped.

Extending beyond the semi-circular portion of each jaw, are the locking arms 10 and 13 which have their meeting faces flat and will closely contact when the jaws are closed. Pivoted to the jaw 10 by means of the pin 12, is the latch member 15 carrying the locking member 16, which has projecting therefrom, the fingers 18 and 19 which are made to fit snugly within slots or recesses 20 and 21 of the left and right hand jaws respectively, thereby locking the jaws 2 and 3 together.

It will be noted that when the fingers 18 and 19 are in locking position, their upper surfaces are flush with the upper face of the elevator, so that the continuity of the cylindrical space will not be interrupted. On the left hand side of the locking member 16, there is provided a downwardly extending hook shaped projection 17, which when the fingers 18 and 19 are in the recesses 20 and 21 respectively, will latch over the arm 13 and aid in holding the arms 10 and 13 in a closed position.

It will be observed that while the jaws 2 and 3 are in open position and the latch member 15 rests with its finger 19 in the recess 21, that the clamp may be automatically locked by simply bringing the arms 10 and 13 together. To accomplish this automatic locking of the clamps there is provided bevelled faces 22 and 23 on the jaw 2 and arm 13 respectively, which coöperate with the finger 18 and an inclined surface on the hook 17, whereby when the arms 10 and 13 are brought together the latch will be raised and the finger 18 will be guided into the recess 20 while the hook portion 17 drops over the upper face of the jaw 18.

On the outer sides of the jaws 2 and 3 and intermediate the ends thereof, there is pro-

vided ears or lugs 6 and 7, each being provided with an aperture 8 and 9 for the reception of the usual bail-link C—C which is adapted to be connected to suitable hoisting mechanism.

It will be seen that when the coupling B rests on the upper face of the elevator, a portion of the fingers 18 and 19 will be under pressure of the weight of the string of casing, thereby eliminating any liability of the clamp becoming loose by the separation of the jaws, which often means the dropping of the casing into the well with serious results to the workmen.

15 By the arrangement and design of the locking mechanism the operation of opening the jaws is also greatly simplified, for after the pressure has been relieved from the upper face of the elevator it is only necessary 20 for the operator to grasp the outer end of the jaw 13 with his left hand and the latch 15 with his right hand, then a slight downward pressure with the right hand sufficient to raise the fingers 18 and 19 out of engagement with their respective recesses, also releases the two arms 10 and 13, and a pull in opposite directions with both hands will cause the elevator to swing open for disengagement from the casing.

25 30 Having thus described my invention what I claim as new is:—

1. In a casing or tubing elevator, the combination with semi-circular hinged jaws, of an arm carried by each of said jaws, one of 25 said arms being provided with an inclined portion, a recess provided in the upper face of each jaw, a latch pivoted to one of said

arms and having fingers which rest in said recesses when the elevator is closed for aiding in securing the jaws in closed position, 40 a hook portion provided on said latch having an inclined face adapted to coöperate with the inclined portion of the arm to raise said latch when the arms are brought together and cause the fingers to engage their 45 respective recesses, and a handle integral with the latch.

2. In a casing or tubing elevator, the combination with semicircular hinged jaws, of an arm carried by each of said jaws, a recess 50 provided in the upper face of each jaw, an inclined portion provided on the upper face of one jaw adjacent the recess in the same, a latch pivoted to one of said arms and having fingers which rest in said recesses when 55 the elevator is closed, an inclined portion provided on one of said arms, and a hook portion provided on said latch having an inclined portion adapted to coöperate with the inclined portion of the arm to raise said 60 latch when the arms are brought together and cause the fingers to engage their respective recesses, the inclined portion on the jaw coöperating with one of said fingers to aid in raising the latch when the arms are 65 brought together.

In witness whereof I set my hand and affix my signature in the presence of two subscribing witnesses.

CARL WHITE, JR.
